UNITED STATES PATENT OFFICE.

GILBERT L. CROWELL, JR., OF ARLINGTON, NEW JERSEY, ASSIGNOR TO
THE DOMINICK & HIAFF, OF NEW YORK, N. Y.

DESIGN FOR A BACK FOR BRUSHES.

SPECIFICATION forming part of Design No. 28,093, dated December 28, 1897.

Application filed November 5, 1897. Serial No. 657,575. Term of patent 14 years.

To all whom it may concern:

Be it known that I, GILBERT L. CROWELL, Jr., a citizen of the United States, residing at Arlington, in the county of Hudson and State of New Jersey, have invented and produced a new and original Design for the Backs of Brushes or Similar Articles, of which the following is a specification, reference being had to the drawings accompanying and forming a part of the same.

Figure 1 is a plan view of the back of a brush bearing my design. Fig. 2 is an outline section on plane *a a*.

The general form or outline shape of the back of the brush or similar article is that of the fiddle-shape or pandurate order. The outline form of the handle of the back is of the same general order, but of a narrower oblong and undulates gradually and regularly into the outline of the back.

Crowning the top of the handle is the acanthus-leaf design A, from which extend down-

wardly along both edges of the back the foliate borders B. The lower end of the handle bears the terminate acanthus-leaf design C. 25

D represents a band of shallow fluting, which running along both side edges of the handle and back, practically following the outline edge thereof, extends from the leaf design A to the leaf design C. The contained 30 or central spaces E and F are plain and slightly upwardly curved, as shown in Fig. 2.

The essential features of the design are the two leaf representations and the foliate border. 35

What is claimed as new is—

The design for the back of a brush or similar article, substantially as shown and described.

GILBERT L. CROWELL, JR.
